UNITED STATES PATENT OFFICE

2,178,427

SUCTION NOZZLE

Henry T. Lang, Cleveland, Ohio, assignor to Electric Vacuum Cleaner Company, Inc., Cleveland, Ohio, a corporation of New York

Application April 6, 1937, Serial No. 135,235

1 Claim. (Cl. 15—158)

The present invention relates to suction nozzles for vacuum cleaners.

The object of my invention is to provide an improved construction and arrangement in suction nozzles and for a consideration of what I believe to be novel and my invention attention is directed to the following description and the claim appended thereto.

In the accompanying drawing, Fig. 1 is a rear elevation partly in section of a suction nozzle embodying my invention; Fig. 2 is a sectional end elevation of the suction nozzle; Fig. 3 is a bottom plan view of the suction nozzle, the brush being removed; and Fig. 4 is a perspective view of the nozzle connected to a suction hose.

Referring to the drawing, there is shown a suction nozzle 1 having front and rear surface contacting lips 2 and 3. As shown in Fig. 1 the ends of the lips are lower than the intermediate portions of the lips. During the use of the suction nozzle the intermediate portions of the lips are therefore supported slightly above the surface being cleaned. If the nozzle is used for cleaning a floor covering, the floor covering will therefore be lifted against the intermediate portion of the nozzle lips and will be more effectively cleaned as the nozzle is moved across the floor covering. Projecting from and substantially flush with the rear nozzle lip 3 is a shoe 4, the rear part 5 being at the same level as the ends of the nozzle. The nozzle, therefore, has a three-point support which holds the nozzle lips in alignment with the floor covering. The point 5 is a substantial distance to the rear of the nozzle lips so that a stable support is provided.

On the rear side of the suction nozzle above the shoe 4 is an opening having spaced vertical side walls 6 and an arcuate front wall 7. Between the walls 6 adjacent the shoe 4 extends a pin 8 on which is pivoted a coupling 9.

The coupling has an arcuate wall 10 concentric with the wall 7 and side walls parallel to the walls 6. Suitable gasket material, for example, sponge rubber strips 11, is arranged between the sides of the coupling and the adjacent walls of the opening in the suction nozzle. The end of the coupling within the suction nozzle is open so that the coupling is in communication with the suction nozzle in all of its angular positions.

The discharge end 12 of the coupling is adapted to be connected to one end of a rigid tube 13 the other end of which is connected to a source of suction by means of a flexible hose 14. The upper end of the tube is provided with a bent portion 15 which forms a convenient handle for the operator. The pivotal connection be-

tween the coupling and the suction nozzle permits the angular position of the tube 13 to be changed at will. The pivot pin 8 is located so close to the nozzle lips that there is substantially no tendency to tip the nozzle as it is moved. 5 The lower position of the handle is limited by contact of the lower side of the coupling with the upper surface of the shoe 4. The upper position of the handle is limited by an adjustable stop 16 which contacts the upper edge of 10 the arcuate wall 7.

In the rear side of the front nozzle lip is a recess 17 in which is carried a brush 18. The brush is supported by leaf springs 19 having their ends respectively fixed to the bosses 20 15 and to the brush. The springs 19 normally support the brush in an elevated position in which the bristles are slightly above the nozzle lips. The brush is normally out of contact with the surface being cleaned. Under some circumstances, for example in removing lint from a floor covering, it is desirable that the surface being cleaned be subjected to a brushing action. This is accomplished by lifting the handle 15 thereby causing the handle to pivot about the 25 pin 8 in a counter-clockwise direction as viewed in Fig. 2. This causes the lower end 21 of the wall 10 to contact the upper edge of the brush and force it downward. The leaf springs 19 prevent tilting of the brush. The upper edge 30 of the brush is provided with a rubber covering 22 which reduces the noise caused by the contact of the arm 10 with the brush. When the handle is lowered the springs raise the brush to its normal position. With this construction 35 substantially no effort is required to lower the brush and the brush can be easily held in the lowered position.

What I claim as new and desire to secure by Letters Patent of the United States is:

In a vacuum cleaner, a suction nozzle having front and rear surface contacting lips, a brush within the suction nozzle adjacent the front lip, means including a leaf spring within the nozzle having spaced portions fixed to the nozzle and brush for supporting the brush in a normally elevated position, said springs having sufficient stiffness to prevent twisting under forces exerted by the brush whereby tilting of the brush is prevented, a tubular handle adapted to be connected to a suction hose, a pivotal suction connection between the handle and the nozzle whereby the free end of the handle is movable in a vertical plane, and a part of said handle arranged to engage said brush and force it downward upon lifting of the free end of the handle.

HENRY T. LANG.
